UNITED STATES PATENT OFFICE.

EDMOND M. J. WEINAT AND JOSEPH BOGEY, OF CHICAGO, ILLINOIS, ASSIGNEES, BY MESNE ASSIGNMENTS, OF THREE-FOURTHS TO ANDREW A. BROCK, OF CHICAGO, ILLINOIS.

CARBURETER.

No. 867,859.

Specification of Letters Patent.

Patented Oct. 8, 1907.

Application filed April 7, 1905. Serial No. 254,310.

To all whom it may concern:

Be it known that we, EDMOND M. J. WEINAT, a subject of the Grand Duke of Luxemburg, now residing at Chicago, in the State of Illinois, and JOSEPH BOGEY, 5 a citizen of the Republic of France, now residing at Chicago, Illinois, have invented certain new and useful Improvements in Carbureters, of which the following is a specification.

Our invention relates to carbureters or means for 10 mixing the vapors of volatile oils with air to form an explosive mixture for gas engines and the like. Its primary objects are, to provide automatic means for supplying the air and oil to the mixing chamber and intimately mixing them; to provide a superior spraying device for distributing the vapor of the oil, to provide a superior valve for controlling the outlet of the mixture and a superior means of flooding the carbureter at the beginning of its action, and to generally improve the construction and operation of carbureters. 15 These objects, and other advantages which will hereinafter appear, we attain by means of the construction illustrated in preferred forms in the accompanying drawing, wherein—

Figure 1 is a side elevation of the device; 25 Figure 2 is a plan view of the same; Figure 3 is a top plan view of the air valve and section of the carbureter casing taken along line (3) in Figure 4;

Figure 4 is a central vertical section of the carbureter 30 taken on line (4) in Figure 2;

Figure 5 is a side elevation of the plunger of the vaporizing chamber, and Figure 6 is a central section of the other part of said chamber;

Figure 7 is a partial section of the carbureter taken 35 on line (7) in Figure 4 and showing the outlet valve closed;

Figure 8 is a partial central section showing a modification of the vaporizing chamber having a baffle plate device for facilitating the atomizing of the vapor, 40 and

Figures 9 and 10 are views respectively, of one of the baffle plates and of the ring separating them.

Referring first to Figures 1 to 4, it will be seen that the casing 11 has two air inlets 12, 12^a and an outlet 45 13 for the mixture. It is closed at the top by a cap 14 through which extends the revolving stem 15 of the air valve 16. This valve is engaged on its stem to rotate it, by the head 17 of the lever 18 which is operated by a link 19, or any other handle as may be desired.

50 The head 17 and a rotating collar 17^a are clamped together firmly by means of the two nuts 20 engaging the stem 15 and therefore the handle 18 is frictionally held on said stem. Communication between the lower side of the valve 16 and the upper part of the mixing 55 chamber is secured by means of the perforations 31 (see

Figures 3 & 4) in such valve. The relative position of the handle 18 may thus be adjusted, and its rotation is governed by means of the collar 17, which has a pin 22 working in the inclined slot 21 in the part 22, as shown in Figure 1, for the purpose to be hereafter 60 described.

The gasoline or other oil enters through the pipe 23 and passes upward through the puppet valve 24 which is carried on adjustable stem 25 fixed in the top of a hollow float 26 and guided for vertical movement by extension of its stem into the valve stem 15. The oil enters through the valve 24 into the chamber formed by the cup 27 and the plunger 28 fitting loosely therein, and supports the float 26, which thus automatically operates the inlet valve to maintain a constant level. The 70 plunger 28 has a stem 32 extending into the air valve stem 15, and a spring 34 keeps the plunger in place and at the same time supports the plunger rod 33 which is used to operate the inlet valve 24 by hand, by pressing it down, engaging the stem 25 of said valve. By 75 this means the oil chamber may be flooded at the starting of the engine, to give a richer vapor.

On the outside of the oil chamber 27 is formed a conical flange 30, and the air valve 16 has an inwardly sloping face 16^a coöperating with the flange 30 making a 80 variable opening between them, through which the air from inlets 12 and 12^a is drawn. Immediately above this annular opening the air passage expands, and meets the spray of the oil which is drawn by suction from the chamber 27 through the multiplex small passages between cup 27 and plunger 28, formed by the cross grooves 29 on the surface of the cup; (see Figures 5 and 6.) The lower rim of the plunger 28 is serrated as shown in Figure 5 in order to keep clear passages under the plunger where it rests on the annular ledge in the cup 27. 90 The air valve 16 has an upwardly extended flange or wing 16^b which, when the valve is both elevated and rotated, covers the outlet 13. From Figure 1 it will be seen that this action is effected by rotating the handle 18 which causes the pin 22 to slide in the inclined slot 95 21 and raise the valve 16. The slot has a horizontal portion at the upper end, and further motion of the pin therein, and revolving the valve, causes the wing 16^b to obstruct the mixture outlet 13, thus cutting off the supply to the engine. It will be noted that the upward 100 motion of the valve 16 constricts the air inlet slit between 16^a and 30, and that it entirely closes before the pin 22 strikes the flat portion of the slot 21 and the wing 16^b closes the outlet 13. The proportions of air and gas may thus be altered without interfering with the outlet 105 for the explosive mixture.

While the oil cup and the sliding valve 16 have been shown as circular, it will be understood that these may be of square or other form, the essential feature being the opening and closing of the air inlet by sliding of one 11

of these parts on the other and the oil spray inlet being contiguous to the air inlet. Also the closing wing 16th for the mixture outlet may of course be operated by simple vertical movement of the valve 16 when so desired. It is to be noted that the relative positions of the oil and air inlets causes the oil to be drawn in by suction and requires no pressure in the oil tank or feed pipe 23.

In Figures 8 to 10 we have shown a modified form of 10 the closing plunger of the oil chamber providing additional means for breaking up and mixing the oil vapor with the air. Around an upward extension of the plunger 28 are placed a series of serrated rings 34, spaced by rings 35, and having their respective solid portions 34^a alternated with one another, thus causing the air and 15 vapor to follow a devious path upward and become thoroughly mixed. The structure above described gives a very easy and certain feed of the oil, and the annular air inlet and mixing chamber renders the air feed 20 free, readily controllable, and certain of very uniform and intimate mixture with the vapor. The provision of the multiplex passages 29 allows of very fine spraying of the oil without obstructing the flow. Other advantages will readily occur to those familiar with the art.

25 Having thus described our invention and illustrated its use, what we claim as new and desire to protect by Letters Patent, is the following:

1. In a carbureter, an oil reservoir containing a float and an inlet valve governed thereby, and having an outlet 30 formed by an annular series of multiplex small passages, in combination with an annular air inlet valve for the carbureter surrounding said reservoir.
2. In a carbureter the combination with an annular air inlet valve, of an oil reservoir having an annular outlet 35 for the oil vapor therefrom, adjacent to said air valve, and the air valve seating on the reservoir, substantially as described.
3. The combination with the oil reservoir having an outside face partially conical and an oil outlet adjacent 40 thereto, of a combined air valve and mixing chamber comprising an interiorly conical cup surrounding and registering with the conical surface of the reservoir to form an air inlet valve, substantially as described.
4. In a carbureter, an oil reservoir comprising two 45 telescoping cups, one of the contiguous surfaces of which has outlet grooves a part of which communicate with the interior of the reservoir and a part of which cross the first mentioned part intermediate the ends thereof, and means for forcing the oil through the grooves.

5. In a carbureter, an oil reservoir comprising two 50 telescoping cups, one of the contiguous surfaces of which has a plurality of grooves communicating with the oil reservoir and a plurality of cross grooves intermediate the ends of such first grooves, and means for forcing the oil through the grooves. 55

6. The combination with the casing 11 and the contained oil reservoir, of an annular air inlet valve having a seat on the reservoir, means to move the valve and thereby open and close it, and means on said valve for controlling also the outlet of mixed oil and air from the 60 said casing. 65

7. In a carbureter the combination with the casing having air inlets and an outlet for the mixture, of an air inlet valve closing by sliding vertically in the casing and having a wing controlling the mixture outlet by revolution of 65 the valve, and means for raising and rotating the said valve. 70

8. In a carbureter the combination of a cylindrical casing, a cylindrical oil chamber concentrically located therein and having an oil inlet in its top and a per-conical exterior face, and an air inlet valve comprising a perforated cup fitting in the casing between the casing and said reservoir and having an interiorly conical face cooperating with the cone on the reservoir to open and close the air inlet by vertical movement of the air valve, substantially as described. 75

9. A carbureter valve opening by vertical movement to admit air to the mixing chamber, and having the wing 16th and being revolvable to close the mixture outlet thereby, in combination with a casing having air inlets and an outlet for the mixture, substantially as described. 80

10. In a carbureter the combination with an inclosing casing, of an oil reservoir therein having a sloping outside surface, and a valve between the casing and reservoir surrounding the reservoir and having a sloping surface cooperating with the sloping surface on the reservoir to open and close an air discharge in the casing by relative movement of the said annular valve with respect to the casing, substantially as described. 85

11. In a carbureter the combination with a reciprocating annular valve ring having a sloping surface, of a surrounding casing and an oil reservoir placed within said valve ring and having a surface adapted to open and close the space between the reservoir and the valve ring by reciprocation of the ring, and said oil reservoir having an outlet contiguous to the annular space between it and the valve ring, substantially as described. 90 95

In testimony whereof we have hereunto signed our names in the presence of the two subscribing witnesses.

EDMOND M. J. WEINAT,
JOSEPH BOGEY.

In the presence of:-

PAUL CARPENTER,
ALBERT GRANT MILLER.
